(57) **CLAIM**

The ornamental design for a display screen or portion thereof with an animated graphical user interface, substantially as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first image of an animated graphical user interface for a display screen or portion thereof showing our new design;

FIG. 2 is a front view of a second image thereof;

FIG. 3 is a front view of a third image thereof;

FIG. 4 is a front view of a fourth image thereof; and,

FIG. 5 is a front view of a fifth image thereof.

The broken lines showing a display screen or portion thereof form no part of the claimed design.

The appearance of the image transitions sequentially between the images shown in FIGS. 1-5. The process or period in which an image transitions to another forms no part of the claimed design.
